CUFF HOLDER FOR GARMENT PRESSES

Filed Aug. 6, 1929

UNITED STATES PATENT OFFICE

PHILIP N. BRAUN, OF SYRACUSE, NEW YORK, ASSIGNOR TO THE PROSPERITY COMPANY, INC., OF SYRACUSE, NEW YORK, A CORPORATION OF NEW YORK

CUFF HOLDER FOR GARMENT PRESSES

Application filed August 6, 1932. Serial No. 383,913.

This invention relates to garment presses and has for its object a particularly simple and efficient means for holding and facilitating the pressing of cuffs, such as cuffs on trousers and the like which require, for proper pressing, a different operation from other portions of the garment, which means is readily operable into and out of pressing or operative position, so that the press can be used for general purposes when cuffs and the like are not being pressed.

The invention consists in the novel features and in the combinations and constructions hereinafter set forth and claimed.

In describing this invention, reference is had to the accompanying drawing in which like characters designate corresponding parts in all the views.

Figure 1 is a side elevation, parts being omitted, of a press embodying my invention.

Figure 2 is a fragmentary front elevation of parts seen in Figure 1.

Figure 3 is a fragmentary perspective view of a pressing machine showing how the cuff holder is used in pressing trousers.

Figure 4 is a plan view of the cuff holder and carrier therefor.

Figure 5 is a side elevation of parts seen in Figure 4, the contiguous portion of the support being also shown.

Figure 6 is an end view of the cuff engaging portion of the cuff holder.

In order to properly press the cuffs of trousers so that there are no wrinkles in the trouser legs adjacent the cuffs and so that the cuffs will set properly, it is desirable to stretch or form the cuffs during the pressing operation.

Heretofore, the cuffs have been pressed in a separate operation from that of pressing the trouser legs, when particular attention has been given to the pressing of the cuffs. Ordinarily, no particular attention has been given the pressing of the cuffs and each trouser leg and its cuff pressed at the same time and in the same way with the result that invariably there are flattened down wrinkles in the trouser legs adjacent the cuffs. When particular attention has been given to pressing the cuffs to avoid the wrinkles, the

cuffs have been pressed on a different machine from that on which the trouser legs were pressed.

The invention, therefore, has for its object a machine in which the cuffs can be pressed at the same time that the trousers are pressed and the particular pressing given to the cuffs that has heretofore been done on a separate machine or in a separate operation, and also a machine in which the cuff holding means can quickly be displaced when the machine is used to press garments not having cuffs, or a machine in which the cuff holder is quickly operable, at will, into and out of working position with respect to the pressing elements.

The invention is here shown as embodied in a modern or conventional press comprising upper and lower pressing elements, as a head 1 and buck 2, one of which is movable toward and from the other, as the head 1 movable toward and from the buck 2.

The buck 2 is mounted on a suitable frame 3 and the head 1 is carried by a yoke lever 4 pivoted between its ends at 5 to a standard 6 rising from the frame. The yoke lever forms part of the actuating means for the head. The remainder of the actuating means includes conventional links and levers (not shown) connected to the rear arm of the yoke lever and operated by any prime mover, that is, a pedal or a motor. As many forms of actuating mechanisms are well known, further description is thought to be unnecessary.

7 designates the cuff holder and 8, the support therefor, the support being movable to carry the cuff holder forwardly and rearwardly into and out of juxtaposition to the buck, that is, into and out of a position overhanging one end of the buck 2 with the cuff holder extending lengthwise of the buck, or in a position to receive the cuff of the trouser leg when the trouser leg is laid on the buck in position to be pressed. The work holder comprises a cuff engaging portion 9 and means as a stem 10 slidably mounted in a tubular carrier 11 to be shifted lengthwise of the buck 2. The carrier 11 is pivoted on a horizontal pivot 12 to the support 8, said pivot 12 extending forwardly and rearwardly. A

spring 13 is connected to the carrier 11 to resist pivotal movement thereof.

The work engaging portion is usually a convex flexible plate having stepped portions 14 of different widths for cuffs of different widths.

In operation, the trouser leg is laid on the buck, as seen in Figure 3, and the cuff fitted on the stepped portions 14. The spring 13 holds the holder 7 spaced apart from the buck to facilitate the sleeving of the cuff on the plate 9. The press is then closed and as the head 1 closes, it presses the cuff holder onto the buck and flattens the plate 9 thus stretching, forming and pressing the cuff in the same operation that the leg of the trousers is pressed.

The stiffened concave resilient plate 9, per se, forms no part of this invention.

The support 8 is here shown as a rock arm on a shaft 16 journaled in a bearing 17 provided in a bracket 18 on the frame, the bearing being located below the buck 2 and arranged so that the arm swings fore and aft to carry the cuff holder fore and aft into and out of position over the buck. The carrier 11 is pivoted to the upper end of the arm or support 8. The shaft 16 has another arm 19 thereon for engaging a stop shoulder 20 on the frame to limit the movement of the support, when the cuff holder 7 is over the buck 2. The rock shaft 16 is here shown as power actuated as by a cylinder 21 and piston therein, the piston rod 22 of which is connected to a rock arm 23 on the shaft 16. The piston is single acting and the support 8 and piston are returned to their starting positions, when the pressure in the cylinder is released, by a spring 24.

The flow of motive fluid, as air, to and from the cylinder is controlled by suitable valve means operated by a manual as a push button 25 and trip lever 26. The valve means are well known and form no part of this invention, and insofar as this invention is concerned, the support may be manually or pedally operated.

In operation, when trousers having cuffs are to be pressed, the operator brings the cuff holder 7 over the buck by depressing the button 25. He then lays one trouser leg on the buck and fits the cuff over one of the stepped portions of the holder. He then closes the press, the head in closing, pressing the cuff holder against the buck and flattening or expanding it as before described. He then opens the press and repeats the operation on the other leg and cuff.

If the next garment to be pressed is not a pair of trousers or are trousers without cuffs, the trip lever 26 is operated to permit the cuff holder to return to its starting position.

By this invention, the cuff holder can be instantly brought into and out of working

position and also the trouser leg and cuff can be pressed in one operation.

Although the machine is primarily adapted for pressing trousers with cuffs, it may also be adapted to press other articles with cuffs and the like, as for instance sleeves.

What I claim is:

1. In a garment pressing machine including upper and lower cooperating pressing elements, one of which is movable toward and from the other, and means for actuating the movable element, the combination of a work holder; support means for the work holder, a bearing about which the support means is movable to carry the work holder into and out of position over the lower pressing element, another bearing having its axis disposed at an angle to the first mentioned bearing and about which the work holder is movable under action of the upper pressing element, as the press closes, to carry the work holder toward the lower pressing element; and means for operating the support means.

2. In a garment pressing machine including upper and lower cooperating pressing elements, one of which is movable toward and from the other, and means for actuating the movable element, the combination of a work holder; support means for the work holder movable to carry the work holder into and out of position over the lower pressing element; a movable connection between the work holder and the support means movable under action of the upper pressing element as the press closes, to carry the work holder toward the lower pressing element; and means for operating the support means.

3. In a garment pressing machine including upper and lower cooperating pressing elements, one of which is movable toward and from the other, and means for actuating the movable element, the combination of a work holder; support means for the work holder movable to carry the work holder into and out of position over the lower pressing element; a member connecting the work holder with the support means; a pivotal connection between said member and the support means; a spring associated with said member to yieldingly resist pivotal movement of said member when the work holder is urged toward the lower pressing element; and means for operating the support means.

4. In a garment pressing machine including upper and lower cooperating pressing elements, one of which is movable toward and from the other, and means for actuating the movable element, the combination of a work holder a portion of which is adjustable endwise relatively to the lower pressing element; support means for the work holder movable to carry the work holder into and out of position over the lower pressing element, and movable under action of the upper pressing element, as the press closes, to carry the work

holder toward the lower pressing element; and means for operating the support means.

5. In a garment pressing machine including upper and lower cooperating pressing elements, one of which is movable toward and from the other, and means for actuating the movable element, the combination of a cuff holder having cuff engaging portions of different widths; means for adjusting said cuff holder endwise relatively to the lower pressing element; support means for the cuff holder movable to carry the cuff holder into and out of position over the lower pressing element, and movable under action of the upper pressing element, as the press closes, to carry the cuff holder toward the lower pressing element; and means for operating the support means.

6. In a garment pressing machine including
20 upper and lower pressing elements, one of
which is movable toward and from the other,
and means for actuating the movable element,
the combination of a cuff holder comprising
25 a cuff engaging member, a support therefor
movable to carry the cuff holder into and out
of juxtaposition to the lower pressing ele-
ment, a carrier mounted on the support and
connecting the cuff holder with the support,
and means to shift the cuff holder on the
30 carrier endwise relatively to the lower press-
ing element.

35 7. In a garment pressing machine including upper and lower pressing elements, one of which is movable toward and from the other, and means for actuating the movable element, the combination of a cuff holder comprising a cuff engaging member, a support therefor movable to carry the cuff holder into and out of juxtaposition to the lower pressing element, a carrier being mounted on the support and connecting the cuff holder with the support, and means to shift the cuff holder on the carrier endwise relatively to the lower pressing element, the carrier being also pivoted to the support to effect movement of the holder toward and from the lower element when in juxtaposition thereto.

50 8. In a garment pressing machine including upper and lower pressing elements, one of which is movable toward and from the other, and means for actuating the movable element, the combination of a cuff holder comprising a cuff engaging member, a support therefor movable to carry the cuff holder into and out of juxtaposition to the lower pressing element, a carrier pivotally mounted on the support between the cuff holder and the support, a movable mounting for the cuff holder on the carrier shiftable endwise 55 relatively to the lower element, the carrier being also pivoted to the support to effect movement of the holder toward and from the lower element when in juxtaposition thereto, and a returning spring connected to the pivoted carrier.

9. In a garment pressing machine comprising upper and lower pressing elements, one of which is movable toward and from the other, and means for actuating the movable element, the combination of a cuff holder comprising a cuff engaging member, a support therefor movable to carry the cuff holder into and out of juxtaposition to the lower pressing element, and a tubular carrier mounted on the support and the holder having a stem slidable in the carrier, the carrier being arranged to permit movement of the holder lengthwise of the lower pressing element. 70 75

10. In a garment pressing machine comprising upper and lower pressing elements, one of which is movable toward and from the other, and means for actuating the movable element, the combination of a cuff holder comprising a cuff engaging member, a support therefor movable to carry the cuff holder into and out of juxtaposition to the lower pressing element, and a tubular carrier mounted on the support and the holder having a stem slidable in the carrier, the carrier being arranged to permit movement of the holder lengthwise of the lower pressing element and being pivoted to the support on a substantially horizontal axis to permit movement of the holder toward the lower element by the upper element when the press closes. 95

11. In a garment pressing machine comprising upper and lower pressing elements, one of which is movable toward and from the other, and means for actuating the movable element, the combination of a cuff holder 100 comprising a cuff engaging member, a support therefor movable to carry the cuff holder into and out of juxtaposition to the lower pressing element, a tubular carrier mounted on the support and the holder having a stem 105 slidable in the carrier, the carrier being arranged to permit movement of the holder lengthwise of the lower pressing element, the carrier being pivoted to the support on a substantially horizontal axis to permit movement of the holder toward the lower element by the upper element when the press closes, and a returning spring connected to the carrier to resist pivotal movement. 110

12. In a garment pressing machine including upper and lower pressing elements, one of which is movable toward and from the other, and means for actuating the movable element, the combination of a cuff holder including a cuff engaging member, a support therefor movable to carry the cuff holder into and out of juxtaposition to the lower pressing element, a carrier mounted on the support, a movable mounting connecting the cuff holder to the carrier and shiftable endwise relatively to the lower element, the cuff holder having cuff engaging portions of different widths, a horizontally pivoted mounting for the carrier on the support to permit movement of the holder toward the lower element 115 120 125 130

by the upper element when the press closes and a spring for resisting pivotal movement of the carrier.

13. In a garment pressing machine comprising upper and lower pressing elements, one of which is movable toward and from the other, and means for actuating the movable element, the combination of a cuff holder having a cuff engaging member of different widths, said holder being located at one end of the lower pressing element, a support movable transversely of one end of the lower pressing element to carry the holder into and out of a position overhanging one end of the lower element, a carrier pivoted to the support on a horizontal pivot extending transversely of the lower element, the cuff holder having means slidably mounted in the carrier to permit adjustment of the holder lengthwise of the lower element.

14. In a garment pressing machine comprising upper and lower pressing elements, one of which is movable toward and from the other, and means for actuating the movable element, the combination of a cuff holder having a cuff engaging member of different widths, said holder being located at one end of the lower pressing element, a support movable transversely of one end of the lower pressing element to carry the holder into and out of a position overhanging one end of the lower element, a carrier pivoted to the support on a horizontal pivot extending transversely of the lower element, the cuff holder having means slidably mounted in the carrier to permit adjustment of the holder lengthwise of the lower element, and a spring for resisting pivotal movement of the carrier.

15. In a garment pressing machine comprising upper and lower cooperating pressing elements, one of which is movable toward and from the other, a cuff holder movable into and out of position to overhang one end of the lower element and extending lengthwise thereof, means for actuating the movable element, means for supporting and actuating the cuff holder, and a pivotal connection between the cuff holder and the supporting means so that the movable element may move the cuff holder toward the lower element as the press closes.

In testimony whereof, I have hereunto signed my name, at Syracuse, in the county of Onondaga, and State of New York, this 55 6th day of May, 1929.

PHILIP N. BRAUN.
